PLAYGROUND SPRINKLER

Anita Margrill, 151 W. 13th St.,
New York, N.Y. 10010

Filed Dec. 6, 1972, Ser. No. 312,676

Term of patent 14 years

Int. Cl. D23—01

U.S. Cl. D23—6

FIG. 1 is a front elevational view of a playground sprinkler embodying my new design, the rear being a mirror image of the front shown;

FIG. 2 is a right side elevational view thereof, the left side being a mirror image of the side shown;

FIG. 3 is a top plan view thereof;

FIG. 4 is a bottom plan view thereof;

FIG. 5 is a vertical sectional view thereof taken along the plane of line 5—5 in FIG. 1; and

FIG. 6 is a fragmentary perspective view of a portion thereof.

I claim:

The ornamental design for a playground sprinkler, as shown and described.
